UNITED STATES PATENT OFFICE.

CORNELIA M. POST, OF PHILADELPHIA, PENNSYLVANIA, ASSIGNOR TO
THOMAS POTTER SONS & COMPANY, INCORPORATED, OF SAME
PLACE.

DESIGN FOR FLOOR-CLOTH.

SPECIFICATION forming part of Design No. 34,425, dated April 23, 1901.

Application filed March 30, 1901. Serial No. 53,738. Term of patent 3½ years.

To all whom it may concern:

Be it known that I, CORNELIA M. POST, a citizen of the United States, residing at Philadelphia, in the county of Philadelphia and State of Pennsylvania, have invented and produced a new and original Design for a Floor-Cloth, of which the following is a specification, reference being had to the accompanying drawing, forming part thereof.

As shown in the drawing, the leading features of my design are comprised in the squares A, each having a square *a* therein, and the squares A', each having a square *a'* therein smaller than the squares *a*, the outlines of the respective squares being marked by the bands *b*, *b'*, and *b''* of like character, while the figures are otherwise of contrasting character. In each of the squares A a band *c* of plain color surrounds the band *b'*, within which a ground *d* of plain color has the differently-colored figures *e* and *f* contrasting

therewith. In each of the squares A' a band *c'*, divided into small squares, surrounds the band *b''*, within which a ground *k* of plain color has the differently-colored figures *h*, *i*, and *j* contrasting therewith. Small squares *g* of the band *c'* are of color contrasting with the remainder thereof.

Having described my invention, what I claim as new, and desire to secure by Letters Patent, is—

The design for a floor-cloth substantially as herein shown and described.

In testimony whereof I have signed my name to this specification, in the presence of the two subscribing witnesses, March 28, 1901.

CORNELIA M. POST.

Witnesses:

PERCIVAL H. GRANGER,
JOHN B. RUTHERFORD.
